CLAIM

The ornamental design for a packaging box, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front elevation view of a first embodiment of a packaging box, showing my new design in a closed position; FIG. 2 is a side elevation view thereof;

FIG. 3 is a front and bottom perspective view thereof; FIG. 4 is a front and bottom perspective view thereof, shown in a partially open position;

FIG. 5 is a front elevation view of FIG. 4;

FIG. 6 is a front and bottom perspective view thereof, shown in an alternate closed position;

FIG. 7 is a front and top perspective view of FIG. 6;

FIG. 8 is a front elevation view of a second embodiment of a packaging box, showing my new design in a closed position;

FIG. 9 is a bottom plan view thereof;

FIG. 10 is a side elevation thereof;

FIG. 11 is a front and bottom perspective view thereof; FIG. 12 is a front and bottom perspective view thereof, shown in a partially open position;

FIG. 13 is an alternate front and bottom perspective view thereof; and,

FIG. 14 a front and bottom perspective view thereof, shown in an alternate closed position.
